(57) **CLAIM**

The ornamental design for a nailer, as shown and described.

DESCRIPTION

FIG. 1 is a left side view according to our design;

FIG. 2 is a front view thereof;

FIG. 3 is a top view thereof;

FIG. 4 is a bottom side view thereof;

FIG. 5 is a side perspective view of the nailer in a closed position thereof; and,

FIG. 6 is a side perspective view of the nailer in an open position thereof.

The surfaces of the nailer not shown in the drawing views are understood to form no part of the claimed design.
